SKIRT MARKER AND THE LIKE

Isaac Levin, Brooklyn, N. Y.

Application April 20, 1940, Serial No. 330,661

3 Claims. (Cl. 33—9)

This invention relates to skirt markers and other similar devices for directing by a current of air a stream of powder to accurately produce a sharp visible line or mark by the wearer upon a skirt or other garment while the said garment is being worn.

One object of the invention is the provision of such a device wherein the powder dispensing receptacle is preferably made of flexible rubber and is provided with a normally closed dispensing mouth comprising a pair of lips which are adapted to be parted when the powder is to be dispensed, by the application of air pressure by suitable means provided for that purpose, the said mouth also being adapted to be opened by hand pressure for the insertion of the marking powder or other material.

Another object of the invention is the provision of a device of the nature referred to in which the dispensing receptacle is provided with means for frictionally yet readily adjustably mounting same upon a graduated support or post without the use of any additional securing means.

A further object of the invention is the provision of such a device in which the graduated post is frictionally maintained in a base, the said post comprising a plurality of sections frictionally maintained one within the other and having at the top thereof a cross-head for normally guiding and supporting the dispensing bulb tube, the said cross-head also adapting the device to be used as a hat stand when not used for dispensing purposes.

Among the advantages of my improved skirt marker are the following: (1) The use of a flexible rubber dispensing receptacle which may contain powder or liquid to be dispensed through the mouth thereof, which is normally closed to prevent spilling of the contents, the mouth being actuated to simulate natural breathing by the manipulation of the dispensing bulb; (2) the ready collapsibility of the device for packing same away when not in use; (3) ease in assembling and disassembling the device and maintaining the parts thereof in position without the use of glue, screws or other securing means; (4) the adjustability and control of the flow of marking material from the dispensing receptacle; (5) the ready adaptability of the mouth to receive a plurality of variously shaped solid marking chalks, crayons, etc. Other features of improvement and advantages will hereinafter appear.

Another object is to produce a device of the character described in which the maximum simplicity of construction and operation is secured.

Other objects and advantages will appear as the nature of the improvements is better understood, the invention consisting substantially in the novel arrangement and co-relation of parts herein fully described and illustrated in the accompanying drawings, wherein similar reference characters are used to describe corresponding parts throughout the several views, and then finally pointed out and specifically defined and indicated in the appended claims.

The disclosure made the basis of exemplifying the present inventive concept suggests a practical embodiment thereof, but the invention is not to be restricted to the exact details of this disclosure, and the latter, therefore, is to be understood from an illustrative, rather than a restrictive standpoint.

The inventive idea involved is capable of receiving a variety of mechanical expressions, one of which, for the purpose of illustration, is shown in the accompanying drawings, in which—

Figure 1 is a perspective view of my improved marker and illustrating a convenient method of using same;

Figure 2 is a front view of the device;

Figure 3 is a sectional view thereof, taken on line 3—3 Figure 2;

Figure 4 is a top plan view thereof looking down upon Figure 3;

Figure 5 is a perspective view showing the dispensing receptacle mouth being opened by hand pressure to receive powder from a container;

Figure 6 is a perspective view of the dispensing receptacle carrying a flat piece of solid marking chalk in the mouth thereof;

Figure 7 is a side view of the dispensing receptacle with a sponge in the mouth thereof and

Figure 8 is a side view of a nozzle which may be inserted into the mouth of the receptacle when used as a liquid spraying device.

Referring now to the drawings in detail 10 indicates a base preferably made of a metallic shell and plate 11 and 12 respectively. The said shell and plate are each provided with resilient split hubs 13 for frictionally receiving the lowermost section 14 of a graduated post 15. The said post is preferably made collapsible and may comprise a suitable number of sections, telescopically arranged one within the other, three such sections being shown in the present embodiment of my invention, namely the lowermost section 14, an intermediate section 16 and an upper section 17. The lowermost section 14 is provided with a cylindrical bore 18 into which there is inserted the reduced split end 19 of the intermediate section 16.

for frictional engagement with the bore 18. The upper post section 17 is similarly supported in the bore 20 of the intermediate section 16 into which the lower reduced split end 21 fits. The said upper section 17 is further provided with an upper split reduced end 22 for supporting a cross head 23 which comprises overlapping cylindrical sections 24 and 25 respectively.

Frictionally yet slidably mounted on the post 15 is a powder or liquid dispensing receptacle 26 provided at the rear thereof with an ear, in the bore 28 of which there are provided a pair of rounded in cross section annular ribs 29. These ribs make point contact with the post, thus providing means for frictionally yet readily slidably supporting the receptacle 26 on the post 15 and preventing freezing or sticking of the ear to the post. Any suitable number of such ribs may be provided.

The dispensing receptacle 26 is provided at the front thereof with a normally closed mouth 30, the said mouth comprising an upper lip 31 separated from a lower lip 32 by a line slit 33 through which the contents of the receptacle 26 may be sprayed or dispensed. The spraying or dispensing is accomplished by means of a collapsible and distendable rubber bulb 34 into the mouth of which one end of a rubber tube 35 extends, the other end 35a (see Fig. 3) frictionally extending into the interior of the receptacle chamber 36. By thus arranging the tube with respect to the chamber 36, that is by being able to adjust the distance between the end 35a from the contents of the chamber, the force of the air which strikes same when the bulb 34 is compressed may be regulated thus controlling or regulating the amount of powder or other material dispensed from the receptacle 26. It may here be pointed out that due to the line slit 33 the receptacle 26 is practically leak proof, likewise that with each compression and release of the bulb 34 the lips 31 and 32 will open and close thus simulating a natural breathing action and preventing an excess of material from being dispensed, thus insuring a distinct sharp line L to be formed on the garment 37 when the device is used as a skirt marker. The tube 35 may be guided through a slot 38 in the cross head 23 and supported on one of the sections 23, 24 when not in use. The said cross head provides means for converting the supporting stand to a hat rack when the dispensing device is removed.

In Fig. 5, I have shown that by applying hand pressure to the sides, the mouth is opened sufficiently for filling the chamber 36 with powder or other material from a container 40, or for the insertion of the cylindrical end 41 of a spraying nozzle 42 shown in Figure 8.

In Figure 6 I have shown the receptacle 26 provided with a piece of flat marking chalk 43 in the mouth thereof and in Figure 7 I have shown a sponge 44 held between the lips, the said sponge being used to wipe off surfaces when the chamber 36 contains liquid therein.

From the foregoing it will be seen that I have provided a device primarily to be used as a skirt marker, said device however being adapted for use as a hat support, liquid spraying device as well as other purposes. It will further be seen that the device comprises a plurality of parts that may be readily assembled and frictionally held in place without the use of glue, screws, nails or other securing means. Likewise due to the construction of the mouth, the device is adapted to hold solid chalk, either flat or round in cross section as well as other contrivances. Furthermore, due to the rounded annular rings or ribs 29 in the supporting ear, the receptacle 26 can be easily moved up and down on the graduated post and yet frictionally held in any adjusted position. Also that the amount of material dispensed is easily controlled due to the adjustability of the tube 35 within the interior of the receptacle 26. It will also be seen that the entire device may be readily disassembled and contained within a small box when not in use.

It should be noted, in addition to the foregoing, that I have produced an article of this nature, which is not only a practical device economical in manufacture and simple in construction, but provides the user with a device of this character at a minimum of cost and which can be readily adapted not only as a skirt marker, but for several other useful purposes, without the addition of any other accessories.

Having described my invention, what I claim as new and desire to secure by Letters Patent is:

1. In a device of the nature described, a base, a post supported on the said base, a receptacle on the post, the said receptacle having an ear, and rounded annular beads on the said ear for frictionally yet slidably engaging the post.

2. For use in a device of the nature described, a resilient flexible powder dispensing receptacle having integral therewith a flat spout extending forwardly therefrom, the spout being slit along its outer end, the slit dividing the mouth into normally closed lips, and air pressure means opening into the interior of the receptacle for forcing air into the receptacle to open the mouth upon the application of pressure to the said means and expel the powder through the said mouth, the lips returning to a closed position when the pressure is released.

3. For use in a device of the nature described, an integral flexible resilient rubber receptacle for containing material to be dispensed, a slit mouth on the said receptacle, the slit dividing the mouth into normally closed lips, air pressure means for operating the said mouth for expelling the material in the receptacle through the mouth thereof, an ear on the receptacle formed with a vertical bore, and a post passing through the bore of the ear and gripped by walls of the bore for frictionally yet slidably supporting the receptacle on the said post.

ISAAC LEVIN.
